BOILER CLEANER

Charles S. Turner, Detroit, Mich., assignor, by
mesne assignments, to Diamond Power Spe-
cialty Corporation, Detroit, Mich., a corpora-
tion of Michigan

Original application February 15, 1930, Serial No.
428,721, now Patent No. 1,992,336. Divided and
this application January 25, 1935, Serial No.
3,478. In Great Britain March 21, 1933

11 Claims. (Cl. 122—392)

This invention relates to boiler cleaners and has particular reference to a boiler cleaner of the type which includes means for discharging jets of cleaning fluid adjacent portions of the boiler 5 to be cleaned.

One of the primary objects of this invention is to provide in a boiler cleaner of the above mentioned character, means for prolonging the life of the pipes and conduits which are provided for 10 supplying cleaning fluid to the blower elements of the boiler cleaner.

Further the invention contemplates the provision of means whereby the cleaning fluid supply conduits and the like will be maintained relatively cool even during periods when cleaning fluid is not passing through the same.

This application is a division of my co-pending application Serial Number 428,721 filed February 15, 1930, which has now issued as Patent No. 20 1,992,336.

Numerous other objects and advantages of this invention will become more apparent as the following description proceeds particularly when reference is had to the accompanying drawings 25 wherein

Fig. 1 is a semi-diagrammatic elevational view of a portion of a boiler showing my invention applied to the same;

Fig. 2 is a fragmentary side elevational view 30 partly in section of the structure shown in Fig. 1;

Fig. 3 is a sectional view taken substantially on the line 3—3 of Fig. 2;

Fig. 4 is a transverse sectional view through 35 a slightly modified type of construction; and

Fig. 5 is a horizontal sectional view taken substantially on the line 5—5 of Fig. 4.

Referring then particularly to the drawings wherein like reference characters designate corresponding parts throughout all views, the numeral 40 10 designates generally a boiler having upper and lower headers or drums 11 and 12 respectively. Connecting the boiler headers in accordance with the usual practice, is a bank 15 of boiler tubes, the tubes being suitably arranged 45 in rows and the lowermost row or that row nearest the firebox being designated by the reference character 16. The numeral 17 designates a portion of the boiler wall which encloses the boiler drums and tubes.

50 For cleaning portions of the boiler, blower elements are provided, these blower elements being so arranged within the boiler as to discharge cleaning fluid adjacent portions thereof to be cleaned. While these blower elements may be of any desired character, they are diagrammatically

illustrated as crescent shaped members 18 secured as by welding or the like to the boiler tubes 19 of the row 16 of tubes. These crescent shaped members provide cleaning fluid passages 20 with which discharge openings 21 communicate, these openings being arranged so as to discharge cleaning fluid in the desired directions within the boiler.

By integrally uniting the blower element forming members 18 to the boiler tubes 19, it will be 10 understood that the blower element forming members will be maintained relatively cool even during the periods when they are not being supplied with cooling fluid. It is to be understood however, that if desired, the blower elements 15 may be of any desired character, that is either integrally secured to certain boiler tubes as illustrated, or free from connection with the boiler tubes, the present invention being directed more particularly to the means for supplying cleaning 20 fluid to these blower elements or passages.

Referring now more particularly to Figs. 1 and 2, the numeral 25 designates a cleaning fluid supply header which, as illustrated, projects exteriorly of the boiler wall and is preferably provided with a control valve 26. This header extends longitudinally of and lies close adjacent the boiler drum or header 12 with the result that this header is maintained relatively cool by virtue of the cooling influence of the relatively 30 cool drum.

Connecting the header 25 with the blower elements 18 are branch pipes 27 and by reference to Fig. 2 of the drawings, it will be noted that these branch pipes also lie close adjacent the drum 12 35 so as to be cooled by the latter. Additionally, as illustrated in Fig. 3 of the drawings, these branch pipes 27 preferably lie close to the boiler tubes of the bank 15, with the result that besides being maintained cool by virtue of their proximity 40 to the boiler drum, they are also being maintained cool by virtue of their proximity to the relatively cool boiler tubes. The branch supply pipes are shown as being slightly bent as at 28 whereby they may yield slightly to compensate 45 for relative movement between the boiler tubes to which the blower elements are secured and the header incident to differences in expansion and contraction of the header and the boiler tubes.

As thus far described, it will be apparent that 50 the invention provides blower elements suitably located within a boiler for discharging cleaning fluid adjacent portions of the boiler to be cleaned. While these blower elements may be of any desired character, they are preferably integrally 55

united with certain of the boiler tubes of the boiler so that they are maintained relatively cool by these boiler tubes.

The invention further provides a cleaning fluid header which although it is disposed within the boiler is positioned in proximity to and preferably above the boiler drum or header so that it is not only kept cool by the relatively cool boiler drum but is also shielded by the latter from direct contact with the products of combustion and furnace gases. Connecting the supply header to the blower elements are branch supply pipes which possess a degree of yieldability and which also lie close adjacent the boiler drum and also close adjacent the boiler tubes so that these branch supply pipes are likewise maintained relatively cool.

Thus with the construction as thus far described, it will be apparent that the blower elements and the supply pipes and conduits therefor will be protected from destruction by the heat of the furnace even during the intervals when they are not supplied with relatively cool cleaning fluid. Thus the invention provides a construction which may be incorporated in a relatively hot part of the boiler but which will nevertheless possess a relatively prolonged life.

In Figs. 4 and 5, a slightly modified type of construction is disclosed in which boiler tubes 35 and 36 are disclosed as communicating with a boiler drum or header 37. Extending longitudinally of the boiler tubes 35 are blower elements 40 provided with suitable discharge nozzles 41 for directing jets of cleaning fluid adjacent portions of the boiler to be cleaned.

Extending longitudinally of the boiler tubes 36 are blower elements 45, these elements being likewise provided with suitable discharge nozzles 46. As in the previously described form of construction, the blower elements are preferably crescent shaped members welded or otherwise formed substantially integral with their respective boiler tubes, whereby the blower elements are maintained relatively cool.

In this modified form of construction there is disclosed a cleaning fluid supply header 50 which is disposed wholly within the boiler drum 37 and which is therefore fully protected by the fluid or the vapor in this boiler drum. It will be understood that at its ends the header projects exteriorly of the boiler wall and is preferably provided with one or more valves for controlling the flow of cleaning fluid to and through the header.

Connecting the blower elements 40 to the header 50 are branch pipes 51, these branch pipes passing through the wall of the boiler drum 37 and communicating with the blower elements as at 52. It will be noted that even exteriorly of the boiler drum these branch pipes lie close adjacent the boiler drum and their respective boiler tubes and further are shielded from the furnace gases by their respective boiler tubes.

For supplying cleaning fluid from the header 50 to the blower elements 45, branch pipes 55 are provided, these branch pipes being disposed wholly within the vapor space of the boiler. Thus the branch pipes 55 pass through the boiler drum and through the tubes 36 communicating with their respective blower elements by way of fittings 56 disposed within the boiler tubes 36.

In this modified form of construction it will be apparent that the blower elements which are integrally united with the boiler tubes are protected by virtue of their association with the boiler tubes from the extreme heat of the boiler. The main

cleaning fluid supply header is located within the vapor space of the boiler and is thus wholly protected from destruction by the boiler heat. Additionally, the branch supply pipes which connect the supply header to the blower elements are either located wholly within the vapor space of the boiler or partly in the vapor space, and in the latter case are so arranged that even when they are out of the vapor space of the boiler, they lie close adjacent relatively cool boiler parts and are further shielded from direct impingement by the furnace gases and products of combustion.

Thus it will be apparent that the invention provides blower elements which preferably are integrally united with relatively cool boiler parts so as to be maintained relatively cool. Additionally, the invention provides supply pipes and conduits for supplying cleaning fluid to these blower elements, these conduits and the pipes being so arranged that they are also adequately protected from destruction by the heat of the boiler.

For the sake of convenience, the invention has been described as being embodied in a cleaner for cleaning boilers. It will be apparent however, that the inventive principles disclosed may be embodied in a device for cleaning apparatus similar to boilers and it is to be therefore understood that wherever the word "boilers" is utilized, it is to be construed as meaning heat exchange apparatus of any character whatever, while the words "boiler cleaner" are to be construed as meaning a cleaner for any such type of apparatus.

While the invention has been described with some detail, it is to be understood that the description is for the purposes of illustration only and is not definitive of the limits of the inventive idea. The right is reserved to make such changes in the details of construction and arrangement of parts as will fall within the purview of the attached claims.

What I claim as my invention is:

1. In a boiler cleaner for a boiler of the type which includes a header and fluid circulating tubes communicating with said header, a blower element disposed in said boiler for directing cleaning fluid adjacent parts thereof to be cleaned, and means for supplying cleaning fluid to said blower element including a main cleaning fluid supply line located in said header.

2. In a cleaner for a boiler of the type which includes a boiler drum and boiler tubes communicating with said drum, a blower element associated with one of said tubes for discharging cleaning fluid adjacent portions of the boiler to be cleaned, a main cleaning fluid supply header extending longitudinally of said drum and within the same, and a conduit passing through said boiler drum connecting said header to the blower element.

3. In a boiler cleaner of the type which includes a drum and boiler tubes communicating with said drum, a blower element associated with one of said boiler tubes for discharging cleaning fluid adjacent portions of the boiler to be cleaned, a main cleaning fluid supply header located within said boiler drum and extending longitudinally thereof, and a branch supply pipe connecting said header to the blower element, said branch supply pipe passing through a wall of said boiler drum and the portion thereof which is disposed outside of the boiler drum being shielded by the boiler tube from direct impingement by the products of combustion.

4. In a boiler cleaner of the type which includes

a header and a boiler tube communicating with said header, a blower element associated with the boiler tube, a cleaning fluid supply line disposed in said header, and a branch supply pipe connecting said cleaning fluid supply line and said blower element, said branch supply pipe being disposed wholly within the said header and boiler tube.

5. In a boiler cleaner for a boiler of the type which includes a boiler drum and a fluid circulating tube communicating therewith, a blower element associated with the boiler tube, a main cleaning fluid supply header disposed within the boiler drum and extending longitudinally thereof, and a branch cleaning fluid supply pipe passing 10 through the boiler drum and the boiler tube for connecting the blower element to the main cleaning fluid supply header.

6. In a boiler cleaner for a boiler of the type which includes a boiler drum and a boiler tube 20 communicating therewith, a blower element integrally united with the boiler tube and having an inlet opening through a wall of the boiler tube, a cleaning fluid supply header disposed within the boiler drum, and a branch supply pipe connecting the cleaning fluid supply header and the blower element, said branch supply pipe passing 25 through the boiler drum and boiler tube and communicating with the inlet opening in the blower element.

20 7. In a cleaner for a boiler of the type which includes a fluid circulating system and means for heating the fluid circulating through said system, a blower element disposed in said boiler for directing cleaning fluid adjacent parts thereof to be 30 cleaned, and means for supplying cleaning fluid to said blower element including a main cleaning fluid supply line located in the fluid circulatory system of the boiler.

35 8. In a cleaner for a boiler of the type which includes a header and boiler tubes connected to

said header, a blower element disposed in said boiler and having its one end adjacent the header, a main cleaning fluid supply line, and a conduit connecting the main cleaning fluid supply line and the blower element, said conduit being so 5 located with reference to one of the boiler tubes as to be shielded thereby from direct impingement by the products of combustion.

9. In a cleaner for a boiler of the type which includes a boiler drum and boiler tubes communicating at their ends with said drum, a plurality of blower elements disposed in said boiler for directing cleaning fluid adjacent the portions thereof to be cleaned, said blower elements extending longitudinally of the boiler tubes whereby the 15 ends thereof terminate adjacent the boiler drum, a main cleaning fluid supply header, and branches connecting said header to said blower elements, said branches being located adjacent said boiler drum and adjacent certain of said boiler tubes so 20 as to be cooled by the same and said branches being further located in such a position as to be shielded by certain of said tubes from direct impingement by the products of combustion.

10. In a boiler cleaner for a boiler of the type 25 which includes a header and a boiler tube connected to said header, a blower element disposed adjacent said boiler tube, and means for supplying a cleaning fluid to said blower element, said means including a cleaning fluid supply conduit 30 extending through the boiler tube.

11. In a boiler cleaner, the combination with a boiler tube, and a blower element integrally secured to said boiler tube, of means for supplying cleaning fluid to said blower element including a 35 cleaning fluid supply conduit communicating with said blower element through an opening in the boiler tube.

CHARLES S. TURNER. 40
